DESIGN FOR A PUZZLE BOARD

John A. Nevin, Wichita, Kans.

Application June 24, 1942, Serial No. 107,322

Term of patent 3½ years

To all whom it may concern:

Be it known that I, John A. Nevin, a citizen of the United States of America, residing at Wichita, in the county of Sedgwick and State of Kansas, have invented a new, original, and ornamental Design for a Puzzle Board, of which the following is a specification, reference being had to the accompanying drawing, forming a part thereof.

Fig. 1 is a plan view of a puzzle board, showing my new design; and

Fig. 2 is an edge view thereof, partly in section, taken on the line II—II of Fig. 1 looking in the direction of the arrows.

Fig. 1 is hatched to indicate coloring.

I claim:

The ornamental design for a puzzle board, as shown and described.

JOHN A. NEVIN.
